LOUDSPEAKER ACTUATED RESONATING DEVICE FOR MUSICAL REPRODUCTION

Curt R. R. Wolfanger, Elkhart, Ind., assignor to C. G. Conn Ltd., Elkhart, Ind., a corporation of Indiana

Filed June 24, 1965, Ser. No. 85,886

Term of patent 14 years

(Cl. D56—1)

FIG 1

FIG 2

FIG 3

FIG 4

FIG. 1 is a front, top and right side perspective view of a loudspeaker actuated resonating device for musical reproduction, showing my new design;

FIG. 2 is a rear elevational view, to a reduced scale;

FIG. 3 is a left side elevational view, to the same scale as FIG. 2, the right side being substantially a mirror image thereof; and

FIG. 4 is a top plan view thereof, to the same scale as FIG. 2.

The bottom, not shown, is substantially plain and unadorned.

I claim:

The ornamental design for a loudspeaker actuated resonating device for musical reproduction, as shown and described.
